DORIS V. BELKNAP, OF BROOKLYN, NEW YORK, ASSIGNOR TO MONUMENT MILLS, OF HOUSATONIC, MASSACHUSETTS, A CORPORATION OF MASSACHUSETTS

DESIGN FOR TEXTILE FABRIC

Application filed March 31, 1930. Serial No. 35,086. Term of patent 7 years.

To all whom it may concern:

Be it known that I, DORIS V. BELKNAP, a citizen of the United States, residing at 780 St. Marks Avenue, Brooklyn, county of Kings, and State of New York, have invented a new, original, and ornamental Design for Textile Fabric, of which the following is a specification, reference being had to the accompanying drawing, forming part hereof.

In the drawing—

The drawing is a plan view of a piece of textile fabric showing substantially one-half of the design in detail. Except for the two central motifs which are shown complete, the detailed illustration contained between the dot and dash lines and the marginal edges comprises one-half of the design, the same being repeated on the opposite side of the dot and dash lines.

I claim:

The ornamental design for textile fabric as shown and described.

DORIS V. BELKNAP.
